THOMAS STRUTHERS, OF SPOKANE, WASHINGTON.

TARGET.

1,305,022.

Specification of Letters Patent. Patented May 27, 1919.

Application filed August 12, 1918. Serial No. 249,519.

To all whom it may concern:

Be it known that I, THOMAS STRUTHERS, a citizen of the United States, residing at Spokane, in the county of Spokane, State of 5 Washington, have invented certain new and useful Improvements in Targets, of which the following is a specification.

The present invention relates to an improved target especially adapted for use in 10 shooting galleries, etc., wherein a projectile such as a ball from a gun, bullet from a cartridge, a marble, or other projectile, when it strikes the target, will move the same to indicate a hit, and upon striking the bull's- 15 eye will cause the usual audible signal.

The primary object of the invention is the provision of a target apparatus, which, when struck will be moved to change its appearance entirely, as for instance by the lowering 20 of one flag and the raising of another in its place, and in connection with this purpose the invention consists in certain novel combinations and arrangements of parts as will be hereinafter more specifically described 25 and claimed.

In the accompanying drawings one complete example of the physical embodiment of the invention is depicted, the arrangement being according to the best mode so 30 far devised for the practical application of the principles of the invention.

Figure 1 is a front elevation of one of the units of the target, showing it supported upon a base.

Fig. 2 is a sectional view through the base, showing the target in side elevation.

Fig. 3 is a sectional detail view of a part of the target support, showing a channel therethrough for a part of the flag halyards.

Fig. 4 is a detail view of the stationary member of the halyard clutch with which the member in Fig. 3 co-acts to hold the halyard of the flag to be raised by the movement of the target.

In the preferred embodiment of the invention a number of targets are used, the units being similar in construction and operation, and these units are readily attachable to or detachable from a base board 1 which has a

50 top rail 2 extending a suitable distance and at a suitable location in the shooting gallery or other place of use. The targets or units may be arranged in rows and each unit is clamped to the top rail through the instrumentality of a metallic, inverted U-shape bracket 3, a screw 4 being employed to pre-

vent displacement of the target 5. The target *per se* indicated at 5 is a circular plate of suitable metal provided with the usual rings, and in the instance shown in the 60 drawings is in outline of a grotesque human figure, with the head and feet portions projecting above and below the circular plate. At the center of the plate is a bull's eye 6 in the form of a circular opening, through 65 which may be discerned the disk 7 which is of suitable metal and so suspended on the transverse pin 8 that it will ring when struck by the projectile which passes through the opening 7 to make a bull's eye. 70

The disk 7 is suspended between the plate 5 and the integral bracket 9 at the back of the plate, and this bracket is hollow to form a socket to slip over the upper reduced end 10 of the movable post 11, suitable bolts or 75 screws 12 being used to secure the bracket on the top of the post. In this manner the target member and its appurtenances are removably attached, by the set bolts or screws 12 to the top of the post 11. Above the 80 bracket 9 at the back of the target plate another bracket 13 is formed, which is a practical continuation of the integral bracket 9 and this latter bracket also is hollow to form a socket for the flag staff or stem 14, a screw 85 15 being utilized to hold the staff in the socket. The post 11, in normal position is vertical, and is symmetrically positioned with regard to the target member, and the flag staff 14 with its flag also projects vertically above the target and centrally thereof. 90

The post 11 is pivoted on the bracket 3 so that the target may swing back when struck with sufficient force, and to this end the post 11 is provided with a hub portion 95 16 at its base which is pivoted between the two ears 17 and 17' of the bracket 3, a pivot pin or bolt 18 being used to hold the post in between the perforated ears.

Arranged at right angles to the flag staff 100 14 is a second flag staff 19, which, when the target is in normal position, projects to the front in a horizontal position, and this flag staff is preferably hollow and secured in the hollow boss 20 projecting forwardly from 105 the hub 16 to accommodate one of the flag halyards 21 which passes through a channel 22 in the hub and thence through the hollow flag staff 19. This halyard 21 passes backwardly from the hub over a guide pulley 23 110 supported in the bracket 24, and at its lower end has attached thereto a weight 25 located

below the top rail and back of the base board 1. The other halyard 21' for co-
action with the halyard 21 has at the rear of
the base board, a spring 26 anchored to the
5 bracket 27, and these two halyards control
the movement of the flag 28 which is slidable
on the hollow flag staff 19 by means of the
two rings or sleeves 29.

The halyard 21 it will be noted is at-
10 tached to the top of the flag 28 and thence
is passed through the top of the hollow staff
19, back through the hub 16 and over the
pulley 23, and as the weight 25 is of suffi-
cient gravity to overcome the tension of the
15 spring 26, it is necessary, in order to pre-
vent untimely raising of the flag 28, to
pinch or clamp the halyard 21, so that the
weight 25 can not raise the flag except when
this action is desired. The halyard is held
20 or clasped between the two lugs 30 and 31,
the former being a stationary lug on the ear
17' of the bracket 3, and the latter being a
movable lug on the hub 16 of the post 11.
Thus, when the target is standing upright
25 as in Figs. 1 and 2, the lug 31 bears up and
holds the halyard 21 between it and the lug
30 on the ear 17', but when the target is
struck and is turned back on its pivot, these
two lugs are parted and the halyard is free.
30 The weight, however can not fall unless
it is freed from the suspending arm 32 which
has a plate 33 to receive the weight, and
the arm is pivoted at 34 to a pivoted lever
35 in the form of a segment of a circle piv-
35 oted at 36 at the rear of the bracket 3.
This lever is shown in normal position in
Fig. 2 with its end resting against the back
of the post 11 of the target, and is used to
return the target to normal position after
40 being knocked down by a projectile through
the instrumentality of a pull cord or rod 37,
bell crank lever 38 pivoted at 39 on the
bracket 40, and the connecting rod 41 be-
tween the bell crank lever and the return
45 lever 35.

Thus when the target is struck (if on the bulls eye the "bell" rings) the impact will cause the target member to swing back on its pivot 18. The return lever 35 is swung
50 back on its pivot 36 and the suspending
lever 32 swings down and to the right in
Fig. 3, from beneath the weight 25. As the
target swings back, the flag staff 19 and its
flag 28 swing to upright position until they
55 assume the vertical position formerly held
by the target, and the two jaws or lugs 30
and 31 are separated by the swinging move-
ment of the post 11 so that the halyard 21
is freed from the jaws. The suspending
60 lever 32 is also freed from the weight 25,
and consequently the weight 25 raises the
flag 28 to the top of the flag staff 19 as the
latter swings to upright position, the po-
sition of the weight in this condition being
65 indicated by dotted lines Fig. 2.

The target is returned to normal posi-
tion by a push on the rod 37, and this re-
turn movement of lever 35 raises the sus-
pension lever 32 and with it the weight
25, the retraction of the spring 26 taking
up the slack of the halyards 21' and 21,
and when in final position, the halyard 21
is again gripped by the jaws 30, 31.

At the front of the target a pair of spring
fingers 42 42 are provided for retaining a
75 placard 43, shown in dotted lines Fig. 1,
upon which placard may be printed or ex-
hibited suitable advertising matter, informa-
tion, etc.

Claims—

1. The combination with a pivoted post
and its target member, and a flag staff ar-
ranged at right angles to the post, of a flag
slidably supported on the staff, and means
for automatically raising the flag as the staff
85 is swung to upright position.

2. In a target, the combination with an
upright, pivoted post and its target member,
and a flag staff arranged at an angle to the
post, of a flag slidably supported on the
90 staff, means for holding the flag in lowered
position, and means automatically actuated
for raising the flag as the staff is returned to
upright position.

3. In a target, the combination with an
upright pivoted post and its target member,
and a flag staff arranged at an angle to the
post and rigid therewith, a movable flag sup-
ported on the staff and a pair of halyards
for the flag, means for holding the halyards
100 with the flag in lowered position, and auto-
matic means for raising the flag as the staff
is turned to upright position.

4. The combination in a target with an
upright pivoted post and its target member,
105 of a flag staff arranged at an angle to the
post, and a movable flag on the staff, of hal-
yards for the flag, means co-acting to hold
the flag in lowered position and adapted to
be released as the staff turns to upright posi-
tion, and means for operating the halyards
110 to raise the flag as the staff is turned to up-
right position.

5. The combination in a target with an
upright pivoted post and its target member,
115 of a flag staff arranged at an angle to the
post, a movable flag thereon and halyards
for the flag, of means co-acting to hold the
halyards with the flag in lowered position, a
spring attached to a halyard for lowering
120 the flag, and a weight attached to the other
halyard for raising the flag as the post is
turned back on its pivot.

6. In a target the combination with a tar-
get-post and its target member, of a flag
staff arranged at an angle to the post and
flag thereon, of a support for the post hav-
ing a fixed jaw, halyards for the flag and
means for co-acting with the halyards to
raise and lower the flag, and a jaw on the
130

post co-acting with the fixed jaw for holding the flag in lowered position.

7. In a target, the combination with a target post and its target member, of a flag staff arranged at an angle to the post and flag thereon with halyards, of a support for the pivoted post formed with a jaw, a spring at-
5 tached to one halyard for lowering the flag and a weight attached to the other halyard for raising the flag, and a jaw on the post 10 co-acting with the fixed jaw, for holding the halyards with the flag in lowered position.

In testimony whereof I affix my signature.
THOMAS STRUTHERS.
